UNITED STATES PATENT OFFICE.

CLIFFORD E. HARRISON, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA.

STOKER-ADJUSTING MECHANISM.

Application filed February 4, 1925. Serial No. 6,780.

My invention relates to stokers, and it has for one object the provision of mechanism that shall permit a quick change in the stroke of one or more fuel pushers.

Another object of my invention is to provide mechanism of the class described that shall be adapted to permit a change in stroke of the driven apparatus during the normal operation of the same, thus avoiding the necessity of shutting down the stoker mechanism.

A further object of my invention is to provide stroke-adjusting mechanism comprising a driving member, a driven member having a slot terminating in at least one abutment at one end and a plurality of abutments at the other end, a supporting pin extending from said driving member into said slot, a tongue extending from said pin and so movable as to engage the desired one of said plurality of abutments, and means tending to maintain said tongue in the position necessary to engage the desired abutment.

Other objects and applications of my invention, as well as details of construction and operation, whereby my invention may be practiced, will appear more fully hereinafter, when taken in connection with the accompanying drawing wherein

Fig. 1 is a vertical sectional view of the front portion of an inclined underfeed stoker embodying my invention;

Fig. 2 is an enlarged detail side elevational view of the stroke-varying mechanism of Fig. 1 adjusted for the maximum stroke;

Fig. 3 is a view similar to Fig. 2 but showing the mechanism as adjusted for the minimum stroke;

Fig. 4 is an end elevational view of the structures of Figs. 2 and 3;

Fig. 5 is a perspective view of the movable tongue and associated shaft portion; and

Fig. 6 is an elevational view of the weighted member that is designed to actuate and thereafter to maintain the tongue of Fig. 5 in either of the positions shown in Figs. 2 and 3.

In the illustrated embodiment of my invention shown in the drawings, a structure 1 of the inclined underfeed type comprises any suitable number of sets of tuyères 2, arranged in stepped formation and extend-

ing downwardly from a furnace opening 3 in a front wall 4 of a furnace 5. Between each pair of tuyères is an elongated chamber 6 that extends downwardly from the furnace opening 3 and it may be supplied with fuel from a hopper 7 which delivers into a casing 8 opening directly into the upper end of the chamber or retort 6. The fuel may be positively fed from the casing 8 by means of a ram 9. The latter is operatively secured by a connecting rod 11 to a crank 12 actuated by a fluid motor 13 or other source of power.

The fuel may be forced from each of the retorts 6 up on to the tuyères 2 by means of plungers 14 and 15 which are slidably mounted on base plates 16 and 17, respectively, disposed adjacent to the base of the retort 6. Inasmuch as it is desirable to vary the rate at which the fuel is advanced from the retorts 6 up on to the tuyères 2, it has heretofore been the practice to provide stroke-varying means 18 of the form shown in Fig. 1. As therein illustrated, a driving member 19, which is pivotally secured at 21 to the connecting rod 11 and at 22 to a pivotal arm 23 extending from a supporting section 24 of the furnace framework, is pivotally secured at 25 to a sleeve 26. The sleeve 26 is movable on a rod 27 intermediate spaced abutments 28 and 29. The rod 27 may be secured to an extension grate rod 31 to be reciprocated.

When the connecting rod 11 is actuated in accordance with the movement of the crank 12, the driving member 19 is reciprocated about the pivotal supporting point 22, thus causing the sleeve 26 to engage successively the abutments 28 and 29 and the grate rod 31 to be moved in opposite directions. With such construction, the stroke of the extension grate rod 31 may be varied only by mounting one or more washers 32 on the rod 27 intermediate one of the abutments 28 and 29 and the reciprocating sleeve 26. As will be readily apparent, the positioning or removal of the washers 32 would necessitate the shutting down of the stoker mechanism and thereafter the removal of the associated parts.

In accordance with my invention, the above-noted undesirable results are entirely eliminated and the adjustment of the stroke

- of the plungers 14 and 15 may be effected during the normal operation of the stoker driving mechanism. Referring to the drawings, the rams 14 and 15 have pusher rods 33 and 34 associated with the driving member 19 through special connections 35 and 36, respectively. Since these connections are fundamentally the same, only one connection will be described in detail, say 35.
- 10 The connection 35 may comprise a pin or so-called power-transmitting element 37 (Fig. 5), ends 38 and 39 of which are respectively journaled in elongated members 41 and 42, forming the driving member 19.
- 15 The members 41 and 42 may be secured in this relation by bolts 43 and spacer tubes 44 (Fig. 4). The outer end of the pusher rod 33 is provided with a main longitudinally extending slot 45, inner and outer ends 46 and 47 of which are designed to serve as abutments. The slot 45 is of such dimensions as to receive the pin 37, whereby a 20 slideable support may be provided by the driving member 19 for the outer end of the pusher rod 33. An upper side 48 of the slot 45 engages the pivotal supporting pin 37, 25 constituting a track for the same.

An inner side of the supporting pin 37 is provided with a projecting tongue 49 which is movable in the slot 45, in accordance with the operation of the driving member 19, into and out of engagement with the inner abutment 46. An opposite side of the shaft 37 is movable into and out of engagement with the outer abutment 47 formed by the slot 45. Thus the reciprocation of the pin 37 and the tongue 49 occurring upon the operation of the crank 13 causes a predetermined motion to be imparted to the plunger 14.

According to my invention, the stroke of the plunger 14 may be varied by providing a second abutment 51 for the end of the pivoted tongue 49. As shown, the abutment 45 51 may comprise an inner end of a recess 52 formed in a lower wall 53 of the main slot 45. A lower side 54 of the recess 52 constitutes a lower track for the tongue 49. An opposite end 55 of the recess 52 may be 50 inclined parallel to the plane of the tongue 49 when the latter is positioned to engage the lower track.

When the driving member 19 is actuated so as to cause the tongue 49 to engage the inner abutment 51, motion is imparted to the plunger 14 and the extent of this motion is dependent upon the spacing of the abutments 47 and 51. In the present illustration, the stroke of the plunger 14 is increased over that afforded by the upper track 48. When the driving member 19 moves in an opposite direction, the supporting pin 37 is actuated into engagement with the outer end 47 of the main slot 45, inasmuch as the pin 37 60 is mounted in alignment with the same, and

the engagement with this end of the slot 45 causes a return movement of plunger 14.

In order that the tongue 49 may be retained in either of the positions just described but yet be manually movable from one to the other, I provide a weighted member 50 of the form shown in Fig. 6. This member is provided with a perforation 56 for the slideable reception of the end 39 of the supporting pin 37. The latter is provided with a projecting tongue portion 57 which is partially disposed within the perforation 56. The outer end portion of the perforation 56 adjacent to the tongue 57 is provided with inwardly extending sections 58 forming oppositely disposed pairs of shoulders 59, 61, and 62, 63. The shoulders of each pair engage the opposite sides of the tongue 57 on opposite sides of the axis thereof, whereby the weighted member 50 may be actuated a predetermined distance independently of the pin 37 and the tongue 49.

The extent of the predetermined movement just mentioned is illustrated in Figs. 2 and 3. In the former figure, the position of the weighted element 50 is such that it tends to cause the tongue 49 to engage the lower track 54 formed by the recess 52, whereas in the latter figure, the position of the weighted member 50 is such that the tongue 49 is caused to engage the upper track 48 formed by the main slot 45. Hence, it is apparent that by actuating the weighted member 50 in the proper direction, the tongue 49 may be moved from co-operative relation with one abutment into co-operative relation with another abutment and thereafter retained in either position with a force determined by the weighted member 50.

In operation, assuming the tongue 49 in its lower position shown in Figs. 1 and 2, the operation of the crank 12 causes the pin 37 and the tongue 49 to co-act with the respective abutments 47 and 51, imparting the maximum stroke to the plunger 14. When it is desired to change the stroke of the plunger 14, the weighted member 50 is actuated from the position shown in Figs. 1 and 2 to that shown in Fig. 3, wherein the tongue 49 is caused to engage the upper track 48. The reciprocation of the driving member 19 then causes the pin 37 and the tongue 49 to engage the respective abutments 47 and 46, imparting a stroke to the plunger 14 which is less than that afforded by the lower track 52.

While I have shown only one form of embodiment of my invention, for the purpose of describing the same and illustrating its principles of construction and operation, it is apparent that various changes and modifications may be made therein without departing from the spirit of my invention, and I desire, therefore, that only 130

such limitations shall be imposed thereon as are indicated in the appended claims or as are demanded by the prior art.

I claim:

5. 1. In combination, a pair of movable members, and means for providing a lost-motion connection therebetween, said means including an element movable from one predetermined position to another so as to vary the stroke of one of said members, and a weighted operating member for said movable element tending to maintain the same in either of said positions.

15. 2. A driving member, a driven member, and means for so connecting said members that the stroke of one of said members may be varied, said means comprising a pair of tracks formed on one of said members and an element carried by the other and movable 20 from one track to the other.

25. 3. A driving member, a driven member, and stroke-varying means interconnecting said members, comprising a movable element carried by one of said members, the other of said members being provided with spaced abutments defining a plurality of tracks, said element being movable from one track to the other.

30. 4. In combination, a driving member, a driven member, and means for operatively associating the same, whereby said driven member may have a plurality of strokes, one of said members being provided with a pair of spaced abutments, said means including an element movable into engagement with one or the other of said abutments, said element being weighted to retain the same in any one of a number of predetermined positions.

40. 5. Stroke-adjusting apparatus comprising swinging driving and driven members, and means for so interconnecting said members as to provide an adjustable lost-motion connection therebetween, one of said 45 swinging members having a pair of spaced abutments providing separate strokes therefor, said means including an element carried by the other of said swinging members and movable into engagement with one 50 or the other of said abutments depending upon the desired stroke.

55. 6. In stroke-adjusting mechanism, the combination with a driving member, of a driven member, and means for so operatively associating the same that said driven member may have a plurality of strokes, said driven member being provided with a pair of tracks having one part in common, said means including an element movable 60 on one or the other of said tracks.

65. 7. In stroke-adjusting mechanism, the combination with a driving member, of a driven member, means for so operatively associating the same that said driven member may have a plurality of strokes, said

driven member being provided with a pair of tracks having one part in common, said means including an element movable on one or the other of said tracks, and means tending to retain said element on the desired track.

70. 8. In stroke-adjusting mechanism, the combination with a driving member, of a driven member, means for operatively associating the same, whereby said driven member may have a plurality of strokes, said driven member being provided with a pair of tracks having one part thereof in common, said means including an element carried by said driving member and movable 80 into engagement with one or the other of said tracks, and a weight so associated with said element as to tend to maintain the same in engagement with the desired track.

85. 9. Stroke-adjusting apparatus comprising a pivoted tongue adapted to engage successively a plurality of abutments spaced to afford strokes of different lengths, and a weighted member so associated with said element that it tends to maintain the same 90 in a position to engage the desired abutment.

10. Stroke-adjusting mechanism for a stoker ram comprising a fulcrumed member adapted to engage successively a plurality of abutments spaced to afford the ram different strokes, and means having a lost-motion connection with said member movable between predetermined positions, said means being operable in each position to exert a force on said member tending to maintain 100 the same in a position to engage the desired abutment.

11. Stroke-adjusting mechanism for a stoker ram comprising a power-transmitting element adapted to engage successively a plurality of abutments defining different strokes for said ram, and means for actuating said movable element but having a lost-motion connection therewith, said means in one position tending to cause said element 110 to engage one of said abutments and in another position to cause said element to engage another of said abutments.

12. In combination, a driving member, a driven member having an abutment, means for slidably mounting said driven member on said driving member, said means having a projecting portion movable into engagement with said abutment, and means operatively associated with said first-mentioned 120 means tending to maintain said projecting portion in a position to engage said abutment.

13. A driving member, a driven member having a plurality of spaced abutments, means for slidably mounting said driven member on said driving member, means extending from said first-mentioned means so as to be movable from a position to engage one abutment to a second position permit- 130

ting engagement with another abutment, and means tending to maintain said second-mentioned means in one or the other of said positions.

14. A driving member, a driven member having a longitudinally extending slot, a pin mounted on said driving member and movable in said slot, and a tongue projecting from said pin and movable into engagement with one end of said slot, whereby motion may be imparted to said driven member during at least a portion of the stroke of said driving member.

15. A driving member, a driven member provided with a longitudinally extending slot, a pin extending from said driving member into engagement with said slot so as to provide a slidable support for said driven member, means extending from said pin so as to be movable into engagement with one end of said slot, whereby motion may be imparted to said driven member during at least a portion of the stroke of said driving member, and means tending to maintain said projecting portion in engagement with one wall of said slot.

16. A driving member, a driven member having a slot adapted to receive a supporting pin extending from said driving member, said pin being movable into engagement with one end of said slot when actuated in one direction, and a tongue extending from said pin and movable into engagement with the other end of said slot when said driving member is actuated in the opposite direction.

17. A driving member, a driven member having a slot providing at least one abutment at one end and a plurality of abutments at the other end, a pin for supporting said driven member on said driving member, and a tongue extending from said pin adapted to cooperate with the desired one of said plurality of abutments.

18. A driving member, a driven member having a slot providing at least one abutment at one end and a plurality of abutments at the other end, a pin for supporting

said driven member on said driving member, a tongue extending from said pin adapted to engage one of said plurality of abutments, and a weighted element so mounted on said pin as to tend to maintain said tongue in a position to engage the desired one of said plurality of abutments.

19. A driving member, a driven member having a slot providing a common abutment at one end and a plurality of abutments at the other end, a pin for slidably supporting said driven member on said driving member, a tongue extending from one side of said pin and adapted to engage one of said plurality of abutments, and a weighted element having such lost-motion connection with said pin that said tongue is retained in the position necessary to engage the desired one of said plurality of abutments.

20. In a stoker, the combination with a reciprocating plunger, and a power source therefor, of adjustable-stroke mechanism for interconnecting the same comprising members respectively connected to said power source and to said plunger, the latter member having a plurality of tracks terminating in abutments, a supporting element extending from the power-driven member and movable in one direction into engagement with one end of said tracks, a projecting portion from said pin movable into engagement with one of the abutments at the other end of said tracks, and means tending to maintain said projecting portion in the position necessary to traverse the desired one of said tracks.

21. Stroke-adjusting mechanism for a stoker ram comprising a driving member, a driven member, one of said members comprising a pair of spaced elements with the other member disposed therebetween and provided with a slot having abutments defining different strokes, and a pin disposed in said slot and mounted on said spaced elements so as to provide a slidable support for said slotted member, said pin being adapted to co-operate with said abutments.

CLIFFORD E. HARRISON.
